UNITED STATES PATENT OFFICE.

HERMANN SCHIERING AND ARTHUR REINHARDT, OF APOLDA, GERMANY.

RAILWAY SIGNALING DEVICE.

Application filed July 11, 1927, Serial No. 204,962, and in Germany July 16, 1926.

This invention relates to an improved railway signaling device for automatically indicating to the driver of a locomotive whether the line is free or blocked, and more particularly to a double switch on the locomotive, one for the signal: line blocked, and the other for the signal: line free.

The improved device is illustrated on the accompanying drawings, in which Fig. 1 shows the same in a side view as mounted on a permanent line and on a locomotive respectively, Fig. 2 is an end view thereof on a somewhat larger scale, Fig. 3 is a plan view of that part thereof only mounted on the permanent line, while Fig. 4 is on a larger scale a vertical central section through the main part thereof lying on the locomotive, and Fig. 5 is an end view of a detail of Fig. 4.

In front of each fore and main signal on a permanent line 1, a movable bar 2 is arranged transversely to and at the foot of the rails of the permanent line and fitted with two upright pins 3, 3^a, said bar being at one end joined by a link 4 to a T-shaped lever 5 fulcrumed on a fixed bolt 6 and connected at its short arms 7 and 8 with wire cords 9 and 10 leading to an adjusting lever 11 to which they are fixed at 12 and 13. Said lever 11 is fulcrumed on a fixed bolt 14. With the wire cords 9, 10, furthermore, the signal arm 15 is connected by means of a lazy tongs 16, the arm 17 of the latter being fixed to the wire cord 9 while the arm 18 is loosely mounted over the wire cord 10. The signal arm 15 is by a connection-rod 19 connected with the free upper end of the lazy tongs 16. By turning the adjusting lever 11, the signal arm 15 is displaced together with the bar 2.

In the driver's stand of the locomotive, according to the present invention, a double turning switch 20 is arranged, of which the common axle 21 projects in downward direction and carries a horizontal double arm 22 which during the run of the locomotive strikes against the abutment-pin 3 underneath and is thereby turned through 90° in one or the other direction. By said turning, one of two signal lamps 23, 24 (a red one for line blocked, and a green one for line free) in the driver's stand is switched-on by means of electric leads connected with the double switch and indicates thus to the driver the actual position assumed by the

signal arm. Said signal lamps are electric glow-lamps inserted in the circuit of an electric current source 25 in which also the double switch is inserted by means of the electric leads mentioned. In said circuit, furthermore, audible alarm signals, for instance electric bells 26, 27 are inserted.

The double turning switch is enclosed by a casing 28 closed at both ends by covers 29, 30, the switch being constructed as follows: The two insulating discs 31, 32 fixed in said casing are fitted with metal sectors 33 on which slide contact springs 34, 35. Said metal sectors are conductively connected with terminals 36 to which the electric leads 70 aforementioned are attached. The axle 21 extends centrally through said casing 28 and through the insulating discs 31, 32 and has at the top a fixed knob 37 for manual operation of the switch. Said axle 21 carries further on a square part thereof axially movable spring-pressed coupling members 38, 39 which at their oppositely directed gripping faces 40 engage in sleeves 41, 42 fixed on the axle 21 and carrying the contact springs 34, 35.

If by the adjusted abutment-pin 3 the double arm 22 is turned in clockwise direction, the lower coupling member 38 causes a rotation of the sleeve 41 whereby the lower switch is operated for switching-on the red signal lamp 23 (line blocked), while the upper switch for the green lamp (line free) 24 remains in its cut-out position as the coupling member 39 slips loosely along the sleeve 42. The driver having then stopped the train, can, by a quarter turn of the axle 21 by means of the knob 37, again cut-out the red signal lamp whereby at the same time the double arm 22 is returned to its original transverse position (Fig. 3). With the signal arm being pulled to line free, the abutment-pin 3 assumes the dotted-line position shown in Fig. 3 and turns then the double arm 22 in counterclockwise direction whereby the upper switch (for the green lamp) is operated while the lower switch (for the red lamp) remains at rest.

The bar 2 is fitted with stops 42^a for ensuring always a correct position of the abutment-pins 3, 3^a with reference to the double arm 22.

The abutment-pin 3^a on the other side of the permanent line is provided for locomotives running with their rear end in forward

direction and having thus the double arm 22 located at the other side of the permanent line.

What we claim, is:—

- 5 1. In a railway signaling device, a double switch on the locomotive of a train, one for the signal "line blocked" and the other for the signal "line free", comprising a casing, two insulating discs fixed in said casing, conductively connected metal sectors and terminals on said discs to which terminals electric leads are attached, a common rotary axle passing through said discs and projecting at both ends from said casing, axially 10 movable spring-pressed coupling members on said axle within said casing, oppositely directed gripping faces on said coupling members, sleeves fixed on said axle and en-
- 15

gaging with said gripping faces, and contact springs carried by said sleeves and in 20 slidable contact with said metal sectors, the engagement between said sleeves and said oppositely directed gripping faces being such that at a rotation of said axle in one direction one switch and at a rotation of said 25 axle in the other direction the other switch is operated.

2. In a double switch as specified in claim 1, a fixed double arm on one projecting end of said axle for its mechanical rotation, and a fixed knob at the other projecting end of 30 said axle for its manual operation.

In testimony whereof we have hereunto set out hands.

HERMANN SCHIERING.
ARTHUR REINHARDT.
